GEAR ASSEMBLY FOR TOTALIZATORS

Awdry Francis Julius, Sydney, New South Wales, Australia, and George Alfred Julius, deceased, late of Sydney, New South Wales, Australia, by Eva Dronghsia Odierna Julius, Killara, near Sydney, New South Wales, Australia, and Awdry Francis Julius and Russell Stuart Hicks, Sydney, New South Wales, Australia, executors, assignors to Automatic Totalizers Limited, Sydney, New South Wales, Australia

Application June 30, 1948, Serial No. 36,170
In Australia June 30, 1947

3 Claims. (CL. 74—348)

1

In race totalizer installations of the kind to which this invention is referable, the odds obtaining in respect of each competitor in the event for which transactions are being effected, are progressively displayed, throughout the particular transaction run, on a number of odds "barometers" or other indicators. Each transaction commences in the issue of a ticket, peculiar to one competitor, from any one of several ticket issuer machines. The issue of each ticket automatically results in a count of one being recorded in a grand total adding unit and also in an adding unit peculiar to the particular competitor. In addition to their other functions, the adding units contribute to the operation of odds computing units for the several competitors. These units are instrumental in actuation of the mentioned display barometers.

A typical odds computing unit for a single competitor comprises two movable elements or "sliders," which for convenience of discussion may be called a "horizontal slider" and a "vertical slider" respectively. The horizontal slider moves horizontally away from a zero or datum point in direct correspondence with the transaction total in respect of its related single competitor, so that the distance of the slider from the datum point is directly proportional to the competitor transaction total. The vertical slider moves vertically away from the datum point in direct correspondence with the transaction grand total in respect of all the competitors in the event, thus the height of the vertical slider from the datum point is directly proportional to the grand total of transactions. The ratio of grand total to competitor total is proportional to the odds for that competitor and this ratio is transmitted to the related barometer by mechanism with which the present invention is not concerned.

In each odds computing unit the recession of the horizontal slider from the datum point is controlled by the related competitor adding unit, by way (for example) of a sprocket chain having one end anchored to the slider and a portion meshing a sprocket wheel on the adding unit. This sprocket wheel is one for which the total rotation is directly proportional to the count of transactions accumulated in its adding unit.

The lift of the vertical sliders above their datum points is controlled by the grand total adding unit, by way (for example) of a sprocket chain having one end anchored to the slider and a portion meshing a sprocket wheel on a line shaft. This line shaft is common to all of the

2

vertical sliders of the computing units for all the competitors, and has a drive sprocket wheel for each. The amount of line shaft rotation is directly proportional to the grand total of transactions accumulated in the grand total adding unit.

A gear assembly forms part of the drive transmission from the grand total adding unit to the mentioned line shaft. This gear assembly is provided to enable the line shaft to be rotated in consonance with a number of changeable operating factors. These factors are particularised in the following paragraphs headed (a), (b) and (c):

(a) It will be appreciated that when the two sliders of an odds computing unit are axially coincident (or nearly coincident) in their common datum point, no tangible odds magnitude is displayable, and that the further the sliders recede from the datum point, the more accurately will the prevailing odds be represented on the barometers. For this reason it is customary to provide each competitor adding unit with more than one sprocket for alternative actuation of its odds computing unit horizontal slider. (For example, there may be two sprockets one of which has twice the number of teeth of the other, this sprocket provision—namely, two sprockets whereof one is twice as big as the other—will now be assumed for convenience of description.) If an event, for which only a small volume of transactions is expected, is to be handled, the larger sprocket may be used, so that the amount of horizontal slider recession, for each transaction, is doubled (to give greater accuracy in odds portrayal). But if the movement of the horizontal slider is doubled, it is necessary to double the value of vertical slider rise in order to keep the odds ratio intact. The mentioned gear assembly is employed to take care of this situation, by including in the assembly a "capacity" gear change ratio whereby the amount of grand total line shaft rotation for a single transaction (recorded by the grand total adding unit) is also doubled.

(b) For "place" transactions the number of dividends payable depends on the number of competitors starting in the event. A common arrangement is to pay three place dividends when there are eight or more starters, and only two when the number of starters is less than eight. When three dividends are payable the transaction grand total is divided into three equal amounts and the odds for each competitor displayed accordingly. When only two dividends

55

are payable the grand total is halved. The odds on a particular starter are therefore different depending on whether it is a three dividend or a two dividend event. Because of this the mentioned gear assembly is furnished with a "dividend" gear change ratio to suit these two different conditions.

(c) Before the transaction grand total is allocated for distribution, or for computation of odds, a percentual reduction is levied on the grand total pool to provide for tax or other governmental charge and to provide for costs and remuneration of the proprietors or lessees of the installation. The levy proportion varies in different states or countries and therefore a function of the mentioned gear assembly is to provide a "levy" gear change ratio so that the rate of grand total line shaft rotation is such as to deduct the particular levy percentage.

The gear assemblies used heretofore are open to objection in several respects. For example, in order to fix a given ratio of rotation between the grand total counter spindle and the line shaft, a large number of manipulations or selections are necessary to give the required levy, dividend and capacity ratios. The first of these manipulations or selections namely, that relative to the levy gear ratio occasions practically no inconvenience because once the levy gear unit giving the required levy ratio is selected, it will remain constant for any given state or country and in any given location for relatively long periods. However, the remaining two manipulations or selections are likely to change from event to event, and as they take considerable time to be carried out, it is a matter of considerable difficulty to arrange when very little time is available, as between successive events for example.

A further disability with existing gear assemblies is in their provision of means whereby the ratio conditions are indicated or represented in a central control room, so that the officer in charge of the installation may be satisfied that the conditions for an impending event are properly established in advance. The control room indicators may consist of lamps, pointers, or the like, which are illuminated or moved in accordance with the particular ratios obtaining at any one time. The prior indicator switch arrangements for this purpose are relatively complex and are a source of trouble unless much attention is devoted thereto by way of servicing, inspection and repair. Again, the arrangement, as a whole, is heavy and cumbersome by reason of the large number of gear wheels and the like incorporated therein and is thus not readily removable from the installation for placement in a different installation, or ready replacement by a reserve gear assembly in the event of failure or breakdown. This last mentioned defect is aggravated by the hitherto usual incorporation of the grand total adding unit at one with the gear assembly, as this makes it unavoidable for the gear assembly to be useless except in association with that particular adding unit. Therefore the gear assembly itself is incapable of being standardised to suit any adding unit irrespectively of whether the adding unit contains only one escapement shaft (as is common in smaller installations) or two or more escapement shafts as in larger installations.

The object of this invention is to overcome the mentioned disadvantages in a relatively simple manner, by the provisions of a gear assembly which is usable with, or separable from, various types of adding units; in which the prior necessity

for several separate gear change manipulations (that is, for capacity and dividend ratio changes) is dispensed with by enabling both of said changes to be accomplished by a single gear change operation, in which particularly simple and effective indicator switch arrangements are incorporated with the single gear change devices, and which in a general manner gives a simpler and more efficient gear assembly in comparison with those devised heretofore.

10 A gear assembly according hereto mainly comprises, a main gear pinion, means for driving this pinion in correspondence with a transaction count accumulating in a grand total adding unit forming part of the totaliser installation, a driven levy gear able to mesh the main pinion, a driving levy gear fixed co-axially to the driven levy gear therewith to constitute a levy gear unit, four driven gears fixed together in coned arrangement, means whereby the driving levy gear may be selectively meshed with any one of the coned gears, and held in selected enmeshment relative thereto, and mechanism for drive connecting the coned gears to a grand total odds-computing line shaft.

20 An example of the invention is illustrated in the drawings herewith.

Figure 1 is a side elevation of a gear assembly. Figure 2 is a plan projected from Figure 1.

30 Figure 3 is a side elevation taken from the reverse side relative to Figure 1.

Figure 4 is a sectional end elevation taken substantially along line 4-4 in Figure 1.

Figure 5 is a side elevation of a gauge block as it would appear in Figure 1 if unobscured.

Figure 6 is a sectional plan taken substantially along line 6-6 in Figure 5.

The several shafts, gears and other parts of the assembly are mounted upon a frame 7 adapted for simple removable mounting (by bolting through brackets 8, for example) upon a bed plate or the like (not shown) which may also constitute a bed for a separate grand total adding unit.

40 45 The main gear pinion 9 is driven in correspondence with a transaction count, as it accumulates in the grand total adding unit, by mechanism which is largely of conventional design. This mechanism includes a sprocket 10 which is rotated by a chain (not shown) meshed with a similar sprocket on the grand total counter spindle.

The sprocket 10 is fixed to one crown wheel 11 of an epicyclic gear unit. This unit is of the common type consisting of two crown wheels 11 and 12 mounted on a pin 13, and a pair of planetary pinions 14 mounted on a centre cross 15.

The crown wheel 11, crown wheel 12, and the centre cross 15 are freely mounted on pin 13.

60 65 The centre cross has a striker arm 16 fixed thereto. When crown wheel 11 is turned "forwardly," the arm 16 is also turned forwardly (anti-clockwise—in Figure 3) by reason of the crown wheel 12, at this stage, remaining stationary due to the loading effect of the gear train (referred to later herein) drive connected thereto.

The forward movement of arm 16 causes a peg 17 thereon to engage between the limbs of a stirrup 18 fixed on the pin 19 of a spring loaded (20) toggle lever 21. This lever has a nose 22 able to close a pair of contacts 23 (shown already closed in Figure 1) to energise a magnetic clutch 24. The driving member 25 of this clutch is rotated continuously. Energisation of the clutch rotates

crown wheel 12 reversely (in comparison with the prior rotation of crown wheel 11) due to the direction of rotation continuously applied to driving member 25 by way (for example) of a belt driven by an electric motor (not shown). This reverse rotation is effected through suitable gears 26, 27, 28 and 29 so that when the sprocket 10 halts (or slows down) the arm 16 will return to re-operate the stirrup 18, and thus the contacts 23 will be re-opened. The magnetic clutch is thus de-energized so that rotation of the crown wheel 12 ceases (due to the relatively heavy inertia loading thereon as previously referred to) when it has turned through the same or substantially the same angle (but in reverse direction) as the original rotation of the crown wheel 11. Crown wheel 12 has a gear wheel 30 fixed concentrically thereto and consequently this gear wheel (although turned reversely to the sprocket 10) has the amount of its rotation directly proportional to the amount by which the grand total counter spindle is rotated. In this regard it will be clear that each reverse part-rotation of wheel 12 may not be exactly angularly equal to the opposite part-rotation of wheel 11 which preceded it, but as these angular discrepancies are not cumulative and are in fact compensated during the next part-rotation of wheels 11 and 12, the final result (following a transaction run of any appreciable duration) is that the amount by which gear 30 is rotated is (in practice) directly proportional to the amount by which the sprocket 10 (turned by the grand total counter spindle) is rotated.

Gear 30 (through suitable gears 31, 32 and 33) turns a shaft 34 which carries the main gear pinion 9. This pinion meshes the larger gear of two gears 35 and 36 which are fixed together. These two gears constitute a levy gear unit. This unit provides (as previously indicated) for the gear change ratio whereby the governmental tax and operating cost proportion of the grand total of transactions is deducted. For example, assuming the total levy amounts to ten percent, then the larger gear 35 may have one hundred teeth and the smaller gear 36 would, in that case, have ninety teeth. If the levy were fifteen percent the larger gear could have one hundred teeth and the smaller eighty-five teeth.

The gears 35 and 36 are coaxially fixed on a boss 37, freely rotatable on a bearing sleeve 38 fixed in the outer end of a swing bracket 39. This bracket is axially slideable and rotatably movable about a bearing sleeve 40 within which shaft 34 is rotatable. The sleeve 40 is fixed to the frame 7 by way of a flange 41 and screws 42. The smaller gear 36 may be meshed with any one of four gear wheels 43, 44, 45 and 46 concentrically fixed together in coned formation, and keyed upon a final drive shaft 47 which is drive connected, by gears 48 and 49, to a sprocket 50 or like wheel for direct operation of the grand total odds-computing line shaft, shaft 47 preferably incorporates a clutch 51 and a crank handle 52, the clutch being disengageable in known manner (by operation of knob 53) to enable the crank handle to be operated for turning the line shaft to reset the grand total sliders of the computing units into their datum point or zero positions.

The four coned gear wheels with which the smaller gear 36 of the levy gear unit may be selectively enmeshed are of such size as to provide for the four changes which in the prior assemblies

could only be made by two gear change manipulations. For example, the gear 46 (when enmeshed with gear 36) gives a line shaft rotation suitable for a two-dividend event at double speed, gear 45 a three-dividend event at double speed, gear 44 a two-dividend event at normal speed, and gear 43 a three-dividend event at normal speed. For this quadruple gear change it is necessary (as previously indicated) for the swing bracket 39 to be not only angularly movable but also movable in an axial or longitudinal direction. The four required positions for the swing bracket, are arranged for by the provision on said swing bracket of a locator pin 54 which is slideable in sleeve 38 and may be screwed (55) within four holes or cavities 56 respectively provided in four step faces 57, 58, 59 and 60 on a gauge block 61 fixed on the gear assembly frame. These step faces have different levels (see Figure 6) equivalent to the axial spacing of the four coned gear wheels, and the holes or cavities in said step faces are circumferentially spaced apart (see Figure 5) by the distances necessary to give correct meshing placement of the gear 36 with any one of the coned gears, thus defining the correct positions resulting from angular and axial adjustment of the swing bracket 39.

The indicator switch arrangements which are preferably incorporated, comprise four spring-loaded press buttons or rods 62, 63, 64 and 65 slideable in an axial direction, within counterbores, aligned with the cavities 56 in the gauge block. The press buttons or rods protrude through holes in a support plate 66 which is fixed relative to the gauge block, and carries four pairs of self opening contacts 67 mounted on spring limbs 68. These limbs 68 act as loading springs for the press buttons, so that when the pin 54 is fully entered into any one of the cavities 56 (as shown in Figure 4) it depresses the related press button, against its spring loading, so that it projects from the rear face of the plate 66 and thus closes one pair of contacts 67, which in time close the circuit for the related indicating device in the control room, thus notifying the correct capacity and dividend ratios for the time being obtaining.

What is claimed is:

1. A gear change mechanism for use with race totalisator odds computing devices comprising, a main gear pinion, a plurality of output gears which are fixed together in coned arrangement, a levy gear unit including a driven gear meshed with said main pinion and a driving gear fixed co-axially to said driven gear for selective engagement with said output gears, a swing bracket provided with a projecting boss and a shoulder portion extending laterally with respect to said boss said swing bracket being axially and angularly movable relative to said main gear pinion and having said levy gear unit freely revolvably mounted thereon, a gauge block having a plurality of stepped face portions corresponding to the number of said output gears against which the shoulder portion of the swing bracket may abut to determine axial alignment of the levy gear unit with said output gears, said gauge block being provided with a plurality of spaced cavities corresponding to the number of output gears within which said boss may be received to determine angular alignment of the levy gear unit with said output gears.
2. A gear assembly according to claim 1 in which the cavities provided in the gauge block include an internally threaded portion and the swing bracket is provided with a locator pin con-

centrically disposed with respect to the boss, one end of the locator pin being threaded for engagement with the threaded portion of the cavities so that the levy gear unit may be locked in axial and angular alignment with the output gears.

3. A gear change mechanism for use with race totalisator odds computing devices comprising a main gear pinion, a plurality of output gears which are fixed together in coned arrangement, a levy gear unit having a driven gear meshed with said main pinion and a driving gear fixed coaxially to said driven gear for selective engagement with said output gears, a swing bracket which is axially and angularly movable relative to said main pinion and whereon said levy gear unit is freely revolubly mounted, a gauge block having a plurality of cavities provided therein corresponding to the number of output gears, a locator pin on said swing bracket which is engageable within any one of the cavities formed in said gauge block, said gauge block being provided with counterbores aligned with said cavities, a press button for controlling an electric

indicating circuit slidably positioned within each of said counterbores so as to be moved by said locating pin when in engagement with a cavity to indicate the position of the levy gear unit.
